UNITED STATES PATENT OFFICE

2,455,530

APPARATUS FOR THE PRODUCTION OF
ARTIFICIAL FILAMENTSRichard W. Stanley, Drexel Hill, Pa., assignor to
American Viscose Corporation, Wilmington,
Del., a corporation of Delaware

Application May 10, 1944, Serial No. 534,870

13 Claims. (Cl. 18—8)

1
This invention relates to apparatus for the production of artificial filaments having irregular denier along their length. The invention particularly relates to a spinning machine in which the spinning material is delivered at a varying rate to the spinnerets so that sections along the filament of heavier denier, which may be called "nubs" or "slubs" alternating with sections of lighter denier.

It has heretofore been suggested to vary the speed of spinning pumps by means of a cam having rises which control the times and duration of operation of the pumps at high speed, the pumps being driven at low speed by a constantly operating mechanism which, however, became disconnected during the intervals of operation at high speed. This system has numerous disadvantages. In the first place, at the instants when the high speed driving connection ceases to function, weak spots which are much smaller in diameter than what should correspond to the normal thin portion of the filaments are produced as a result of the sudden decrease in momentum of the driving mechanism, and because of the play or back lash in the connections with the constantly operating slow speed driving mechanism. In the second place, it is impossible to obtain non-systematic irregularity with respect to the frequency of occurrence of the thick portions of the filaments and with respect to the lengths of the thick portions as compared to that of the intervening thin portions without the use of an extremely large cam and associated parts. It has also been suggested to combine an intermittently operated reciprocating pump with a constant speed rotary spinning pump, but such an arrangement has a limited capacity for variation, the result being generally to produce a variation in the diameters of successive thick portions having relatively short lengths. With this arrangement, it is impossible to obtain long thick portions without making the reciprocating pump of inordinately large size.

In accordance with the present invention, these disadvantages are overcome and the production of filaments having irregular denier in which the thick as well as the thin portions may have various lengths within an extremely wide range and may occur at various regular or irregular intervals is accomplished in a reliable manner without encountering weakened portions of the filaments. This is accomplished by combining the output of a constant volume pump operating at constant speed with a rotary pump which is operated intermittently.

2
The invention will be more particularly described in reference to the drawings, in which—

Figure 1 is a plan view showing a portion of a spinning machine to which the invention is applied;

Figure 2 is a vertical section taken on lines II—II of Figure 1;

Figure 3 illustrates the connections for controlling the auxiliary pumps;

10 Figure 4 is a vertical cross-section, taken on the line IV—IV of Figure 1;

Figure 5 is a vertical section taken on line V—V of Figure 4;

15 Figure 6 is a section of a detail taken on line VI—VI of Figure 5;

Figure 7 is a horizontal section taken on line VII—VII of Figure 8;

Figure 8 is a vertical cross-section taken on line VIII—VIII of Figure 7;

20 Figure 9 is a cross-section of one of the air valves of Figure 3; and

Figures 10 to 12 illustrate various modifications of filaments that are obtainable in accordance with the invention.

25 As shown in Figures 1 and 2, the material to be spun is supplied to the machine through the line 2 through the branch 3 to a positive displacement pump 4, such as a gear or rotary piston pump, from which it discharges through the line

30 5 to the spinneret 6, a plurality of these pumps being driven from the main driving shaft 7 by the gears 8 and 9 respectively, so that the spinning material is supplied by the pumps 4 at constant volume. A filter may be provided in the line 5, though this is not essential. Additional material may be intermittently supplied to each spinneret by the auxiliary pumps 10, which receive the spinning material from the branch 3 through the T-connection 11 and discharge the spinning material through a similar T-connection

35 12 into the discharge line 5 from the main spinning pump 4. The auxiliary pumps 10 are of the rotary type and are preferably also of the positive displacement type, such as a gear or rotary piston pump,

40 and are driven from an auxiliary shaft 13 through the gears 14 and 15 respectively. The auxiliary pump shaft is driven intermittently by mechanism within the housing 16 more particularly shown in Figures 4 to 6.

45 Shaft 13 carries along a portion thereof extending into the housing 16 three members adapted to drive the shaft in one direction only, so that when one of the members is driving the shaft, it can run ahead of the other two members. The

50 first of such members designated by 17 is shown

as a gear mounted rotatably with respect to the shaft 13 and having a suitable one-way clutch connection with the shaft represented for simplicity by the pawl 18 carried by the hub of the gear which co-operates with the ratchet 19 keyed to the shaft 13. The other two members are also connected to the shaft 13 by any suitable one-way clutch again represented in the drawing as a pawl and ratchet system, and these two members are shown as rotatable sleeves 17a and 17b from which the levers 20a and 20b extend to alternate sides of the shaft 13 as indicated in Figure 5. Pins 21 connect the ends of levers 20 to blocks 21' slidably mounted in opposite ways provided in a yoke 22 which carries opposite pistons 23 and 24 arranged to reciprocate within cylinders 25 and 26 respectively. These cylinders communicate with supply lines 27 and 28 respectively of a suitable hydraulic system (more particularly described hereinafter) which is adapted to alternately fill one of the cylinders and then the other, thereby reciprocating the yoke 22 and imparting oscillatory motion to the sleeves 17a and 17b.

It will be apparent that when the yoke moves downwardly, lever 20a rotates the shaft in a counterclockwise direction as viewed in Figure 5. When the yoke moves upwardly, lever 20b causes rotation of the shaft 13, again in a counterclockwise direction.

The gear 17 is driven by a suitable hydraulic motor 29 through the gears 30, 31 and 32. Any suitable form of hydraulic motor may be used, such as a gear or impeller wheel type, the driving fluid being introduced through the pipe 33 and being discharged through the pipe 34. A regulating valve 35 to permit adjustment to obtain any desired constant volume of fluid may be inserted in advance of the hydraulic motor 29 as shown in Figure 3.

The means for controlling the operation of the yoke 22 and of the gear 17 for driving selectively or in combination the shaft 13 is shown in Figures 3, 7 and 8. The controlling means is mounted within the housing 36 and comprises two cams 37 and 38 adapted to be driven either selectively or together from a common driving motor 39. The motor 39 drives a gear 40 through suitable reduction gearing 41. Gear 43 is driven off gear 40. Pinions 44 and 45 are driven by the gears 42 and 43 through the shafts 46 and 47 respectively. Pinion 44 drives the cam 37 through the action of gear 48, shaft 50, pinion 51, and the annular gear 52 which is secured to the cam 37. On the other hand, cam 38 is provided with a ratchet 53 which is intermittently driven by means of the pawl 54 which is rotatably mounted on an eccentric 55. The eccentric 55 is driven by the gear 56 which meshes with pinion 45. A spring 57 presses the pawl 54 into engagement with ratchet 53. A pawl 58 which is pressed by a spring 59 against the ratchet 53 serves to prevent the ratchet from swinging back with the return stroke of the pawl 54.

Referring more particularly to Figures 3 and 9, the action of the cam 37 in the controlling mechanism is transmitted to the yoke 22 in the driving mechanism through the valve 60 which has a plunger 61 resiliently urged by the spring 62 (see Figure 9) to press the pivotally mounted cam follower lever 63 against the cam. The motion of the cam follower 63 alternately from a rise to a recess in the cam 37 alternately directs the fluid entering the valve at 64 through one or the other of the ports 65 and 66 which are connected to lines

27 and 28 respectively. When the fluid is directed through port 65 and line 27 into the upper cylinder 25, the relationships of the valve 60 are as shown in Figure 9, the fluid from cylinder 26 being discharged through line 28, port 66 and discharge port 67. The spring pressed plunger 61a of valve 60a of similar construction presses the cam follower 68 against the cam 38. When the cam follower 68 is in the position shown in Figure 3, the flow of fluid from line 69 through line 34 is prevented by a check valve 10. In this position, therefore, the motor 29 is not operating. However, when the cam follower 68 is swung outwardly by a rise on the cam 38, the fluid from line 69 is directed into line 33a, then through the valve 35, and finally through the line 33 into the hydraulic motor 29. In this position, therefore, the hydraulic motor 29 drives the shaft 13 through the gear 17 and its associated one-way clutch. A branch 33b of line 33a is connected to a cylinder 71 so that when fluid is flowing through line 33a, the pressure therein causes the piston 72 to release the cam follower 63 from further cooperation with the cam 37. In this way, when the hydraulic motor 29 is operating, the operation of cam 37 cannot effect rotation of shaft 13 through the piston system 23 and 24. A valve 13 is provided in line 33b to permit shutting off cylinder 71, if desired. Either of the cam controlling systems may also be temporarily placed out of commission by removing any one of the following elements: cam 37, gear 48, cam 38, or gear 56.

Cams having any relationships between rises and depressions, lengths of rises and lengths of depressions may be substituted for cam 37 or cam 38 or both. From a consideration of the connections illustrated in the drawings, it will be apparent that cam 37 controls the disposition frequency of the short slubs in accordance with the distances between the points of rise and the points of fall thereon, a short slab being formed upon each the filaments at intervals along their length which are proportionate to the distances between each succeeding point of rise and of fall of the cam 37. On the other hand, cam 38 causes rotation of the auxiliary pump shaft 13 throughout the time interval during which the cam follower 68 is traveling over a rise. Therefore, the length of alternate thick and thin portions which are formed by the operation of cam 38 correspond to the arcuate lengths of the alternating depressions and rises in the cam 38.

The invention utilizes the simplicity and versatility of a hydraulic operating mechanism which combines both the reciprocating motor type as illustrated by the pistons 23 and 24 and the rotary type motor shown at 29. By this combination of mechanisms it is possible to obtain in an efficient and reliable manner as wide a variation in the thick and thin pattern of filaments and the yarns composed thereof as may ever be needed in the manufacture of the yarns, cords, and fabrics of knitted, braided or woven structure.

In Figures 10 to 12, several illustrative forms of filaments are shown on a reduced scale particularly as to lengths. Figure 10 shows a type of thick and thin filament which is obtainable when utilizing only the rotary motor 29 for driving the auxiliary shaft 13. The thick portions may be of any length up to several feet, if desired. Figure 11 illustrates the type of thick and thin filament which is obtainable when using only the reciprocating motor 23 and 24 for driving the auxiliary pump shaft 13. The thick portions in this

case may be made of various lengths from a fraction of an inch to an inch or two or longer, if desired. Figure 12 shows a type of filament which is obtainable when utilizing both the rotary and reciprocatory motors for driving the auxiliary shaft #3.

While a preferred embodiment has been shown, it is to be understood that changes or modifications may be made without departing from the spirit and the scope of the invention.

I claim:

1. Apparatus for producing artificial filaments of varying denier comprising a spinneret, a feed line for the material to be spun, a spinning pump having a constant volume discharge rate connected on its suction side to the feed line and on its discharge side to the spinneret, means for driving the pump at constant speed, an auxiliary rotary pump connected on its suction side to the feed line and on its discharge side to the spinneret, a reciprocatory hydraulic motor, a rotary hydraulic motor, and means for selectively connecting each of said motors to said auxiliary rotary pump for intermittently driving the auxiliary pump.

2. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a reciprocable member having a portion thereof extending transversely of, and laterally offset from, the shaft, means for reciprocating the member transversely of the shaft, and clutch means connecting the member to the shaft for transmitting motion of the member to the shaft to rotate the shaft in one direction only.

3. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a reciprocable member having a portion thereof extending transversely of, and laterally offset from, the shaft, means for reciprocating the member transversely of the shaft, and clutch means connecting the member to the shaft for transmitting motion of the member to rotate the shaft in one direction only, and a rotary motor for rotating the auxiliary shaft.

4. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on

its discharge side to the spinneret, an auxiliary shaft for driving the auxiliary pump, means for intermittently rotating the auxiliary shaft comprising a rotatable member on the auxiliary shaft, a reciprocatory motor connected eccentrically to the rotatable member to impart oscillatory motion thereto, and clutch means connecting the member to the auxiliary shaft for transmitting motion of the member to rotate the shaft in one direction only.

5. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a rotatable member on the auxiliary shaft, a hydraulic reciprocatory motor connected eccentrically to the rotatable member to impart oscillatory motion thereto, clutch means connecting the member to the auxiliary shaft for transmitting motion of the member to rotate the shaft in one direction only, and cam means for intermittently operating the hydraulic motor.

6. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to the auxiliary shaft by clutches for independently transmitting motion of the respective members in one and the same direction only to the shaft without interference by the others of such rotatable members, a reciprocatory motor for oscillating at least one of the rotatable members, and a rotary motor for rotating at least one of the rotatable members.

7. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to the auxiliary shaft by clutches for independently transmitting motion of the respective members in one and the same direction only to the shaft without interference by the others of such rotatable members, a reciprocatory motor for oscil-

lating at least one of the rotatable members, a rotary motor for rotating another of the rotatable members, cam means for controlling the intermittent operation of the reciprocatory motor, and additional cam means for controlling the operation of the rotary motor.

8. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to the auxiliary shaft by clutches for independently transmitting motion of the respective members in one and the same direction only to the shaft without interference by the others of such rotatable members, a reciprocatory motor for oscillating at least one of the rotatable members, a rotary motor for rotating another of the rotatable members, cam means for controlling the intermittent operation of the reciprocatory motor, additional cam means for controlling the operation of the rotary motor, a common driving means for the two cam means, and means operatively associated with the additional cam means for preventing operation of the reciprocatory motor during the intervals of operation of the rotary motor.

9. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a reciprocable member having a portion thereof extending transversely of, and laterally offset from, the shaft, means for reciprocating the member transversely of the shaft, and clutch means connecting the member to the shaft for transmitting motion of the member to rotate the shaft in one direction only, a rotary motor, clutch means connecting said motor to the first auxiliary shaft, and means for selectively operating the reciprocating means and the rotary motor.

10. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to

the auxiliary shaft by clutches for independently transmitting motion to the respective members in one and the same direction only to the shaft without interference by the others of such rotatable members, a reciprocatory hydraulic motor for oscillating at least one of the rotatable members, and a rotary hydraulic motor for rotating another of the rotatable members.

11. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to the auxiliary shaft by clutches for independently transmitting motion of the respective members in one and the same direction only to the shaft without interference by the others of such rotatable members, a reciprocatory hydraulic motor for oscillating at least one of the rotatable members, a rotary hydraulic motor for rotating another of the rotatable members, cam means for controlling the intermittent operation of the reciprocatory motor, and additional cam means for controlling the operation of the rotary motor.

12. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the auxiliary shaft, the members being connected to the auxiliary shaft by clutches for independently transmitting motion of the respective members in one and the same direction only to the shaft without interference by the others of such rotatable members, a reciprocatory hydraulic motor for oscillating at least one of the rotatable members and a rotary hydraulic motor for rotating another of the rotatable members, cam means for controlling the intermittent operation of the reciprocatory motor, additional cam means for controlling the operation of the rotary motor, and a common driving means for the two cam means.

13. Apparatus for producing artificial filaments of varying denier comprising a spinneret, a feed line for the material to be spun, a positive displacement pump having a constant volume discharge rate connected on its suction side to the feed line and on its discharge side to the spinneret, a main shaft for driving the pump, means for rotating the shaft at constant speed, an auxiliary positive displacement rotary pump connected on its suction side to the feed line and on its discharge side to the spinneret, an auxiliary shaft for driving the auxiliary pump, means for intermittently rotating the auxiliary shaft comprising a plurality of rotatable members on the

auxiliary shaft, the members being connected to the auxiliary shaft by clutches for independently transmitting motion of the respective members in one and the same direction only to the shaft without interference by the others of such rotatable members, a reciprocating hydraulic motor for oscillating at least one of the rotatable members, a rotary hydraulic motor for rotating another of the rotatable members, cam means for controlling the intermittent operation of the reciprocating motor, additional cam means for controlling the operation of the rotary motor, a common driving means for the two cam means, and means operatively associated with the additional cam means for preventing operation of the reciprocating motor during the intervals of operation of the rotary motor.
